FIG. 3.

UNITED STATES PATENT OFFICE.

OTTO W. PETERSON, OF BERTRAND, NEBRASKA.

AUTOMOBILE.

1,243,549.

Specification of Letters Patent. Patented Oct. 16, 1917.

Application filed December 2, 1916. Serial No. 134,587.

To all whom it may concern:

Be it known that I, OTTO W. PETERSON, a citizen of the United States, residing at Bertrand, in the county of Phelps and State 5 of Nebraska, have invented certain new and useful Improvements in Automobiles, of which the following is a specification.

My invention relates to improvements in automobiles and refers particularly to a 10 device adapted to be attached to the water radiator of all standard makes of machines in which the radiator is located in the front of the engine, and working in conjunction with the water cooling system to more effectively cool the engine.

The primary object of this invention is the provision of a device of this character capable of attachment to machines now in use or at the time of their manufacture, 20 which will concentrate and equally distribute the currents of air created by the fan to all of the cylinders of the engine.

A further object of the invention herein-after described is the production of an attachment of the character and for the purpose stated which will be of simple construction and, inexpensive to manufacture, thereby insuring an efficient device which will be within the reach of all automobile 30 owners.

With the above and other objects in view which will appear as the description proceeds, the invention consists in the novel construction, combination and arrangement 35 of parts hereinafter described and claimed, it being understood that changes in the precise embodiment of the invention herein disclosed can be made without departing from the spirit of the invention.

40 In the accompanying drawings, I have illustrated one complete example of the physical embodiment of my invention constructed according to the best mode I have so far devised for the practical application 45 of the principles of my invention.

Figure 1 represents a side view in elevation of an automobile engine or motor with its radiator and my invention attached thereto.

50 Fig. 2 represents a top plan view thereof, the engine or motor being shown in dotted lines.

Fig. 3 represents a sectional view taken in line 3—3 of Fig. 1, the radiator being 55 shown in dotted lines.

Fig. 4 represents a view in elevation of

the rear of the radiator having my device attached thereto, the main air distributing cylinder or pipe being in section and the water or hose connections of the radiator 60 being omitted.

Fig. 5 represents a bottom plan view of the main air distributing cylinder or pipe.

Fig. 6 represents a sectional view taken on line 6—6 of Fig. 4, and 65

Fig. 7 represents a view in elevation of a portion of the radiator having the plate carrying the screw threaded stud for engaging and securing my invention thereto.

Attention is invited to the accompanying 70 drawings, in which my invention is illustrated as attached to the radiator 1, having the usual water or hose connections 2, leading to the motor or engine 3, all of which may be of any desired design or make.

The invention may be broadly stated as consisting of the main air chamber 4 having the peripheral flange 5 formed thereon and having openings 6 therein engaging the studs 7 carried by the plates 8 secured to the 80 radiator, the winged nuts 9 engaging the studs 7 to prevent the dislodgment of the air chamber, and air distributing cylinder or pipe 10, having the series of openings 11 in its other side and its forward end having formed integral therewith the pair of air conducting pipes 12, leading from the twin outlets 13 of the air chamber and secured thereto by the set screws 14.

Thus it will be seen that my invention is 90 secured to the radiator and the open side 14' of the air chamber is next to the radiator and in this chamber is mounted the air fan 15, having the shaft 16 secured thereto and carrying the pulley 17 which is connected to the pulley 17' carried by the engine crank shaft (not shown) by the belt 18.

As it will be apparent, when the engine or motor 3, is running the fan 15 revolves drawing in the currents of air, which, by 100 action of the fan, are forced through the pipes 12 into the distributing cylinder 10 where the currents of air are blown against the tops of the cylinders of the engine through the openings 11.

The distributing cylinder 10 is entirely supported by the pipes 12 secured to the main air chamber, but if desired the cylinder 10 may be supported or braced from the hood supporting rod 19, by the braces 20, 110 as is illustrated by Fig. 1.

In the machines now in use the fan merely

draws the currents of air through the radiator and consequently against the first cylinder, the rear cylinders receiving none of the cooling air, but my invention overcomes 5 this inherent objection by equally distributing the air to all the cylinders, as hereinbefore stated.

While in the drawings I have illustrated my invention as in use in connection with a 10 four cylinder motor or engine, it will be obvious that it is adapted for use with any number of cylinders, it being only necessary to have the cylinder 10 made practically the same length as the engine or motor.

15 I claim:—

In a system of the character described, the combination with an engine and radiator therefor, of means for concentrating and distributing cool air to said engine, said 20 means consisting of an air collecting chamber having a peripheral flange with openings therein adapted to engage studs carried by

said radiator, binding nuts engaging said studs for detachably securing the chamber to the radiator, a fan mounted on a shaft 25 journaled in said chamber, said fan having connection with the engine, a pair of outlets in the rear of said chamber, a distributing cylinder disposed above the engine and having outlets in its under side, and air 30 ducts leading from said cylinder and engaging the outlets in said chamber, said fan drawing the currents of air through the radiator and forcing the same through the air ducts and out the outlets in said distributing cylinder directly upon the engine, substantially as described.

In testimony whereof I affix my signature in the presence of two witnesses.

OTTO W. PETERSON.
